UNITED STATES PATENT OFFICE.

EUGENE J. STANTON AND LOUIS G. ROBERTS, OF NASHUA, NEW HAMPSHIRE.

SELVAGE-TRIMMING MECHANISM.

Application filed February 19, 1925. Serial No. 10,343.

This invention relates to mechanisms for cutting off threads extending from the selvage edge of a web of cloth.

The weaving of a pattern fabric in a box loom results in the formation of loops of filling at the selvage edge on the drop box side of the loom where changes are made in the color of the filling to produce the desired pattern. Such loops are herein referred to as "loose threads" since they are not woven into the cloth. Such threads must be trimmed by hand after the cloth has been removed from the loom and this operation is known as "selvage trimming."

The present invention involves a mechanism for automatically performing the selvage trimming operation and it is the chief object of the invention to devise a mechanism of this character which will perform the work neatly and economically. The invention further aims to devise a selvage trimmer which will be simple in construction, economical to manufacture, reliable in operation, and which will require a minimum of care and attention on the part of the operator or machine attendant. The preferred embodiment of the invention is designed for use in a loom and is arranged to be operated by the loom. But it is contemplated that it may also be used independently of a loom or in some machine for operating on cloth.

The nature of the invention will be readily understood from the following description when read in connection with the accompanying drawings, and the novel features will be particularly pointed out in the appended claims.

Referring now to the drawings,

Figure 1 is a plan view of a mechanism embodying this invention, showing it mounted in a loom;

Fig. 2 is a front elevation of certain parts of the mechanism shown in Fig. 1;

Fig. 3 is a side elevation of the mechanism shown in Fig. 1;

Fig. 4 is a cross sectional view on the line 4—4, Fig. 1;

Fig. 5 is a cross sectional view on the line 5—5, Fig. 1;

Fig. 6 is a diagrammatic plan view of certain parts of this mechanism and the loom parts associated therewith; and

Fig. 7 is a perspective view of the grippers or fingers which form part of the mechanism shown in Fig. 1.

Referring first to Fig. 6, a portion of a

web of cloth being woven is indicated at W. Assuming that the main body of this cloth is white, and that B is a blue stripe, it will be evident that a white loop of thread w will be formed at the selvage edge extending across the stripe B, and that a blue strand of thread f will run from the edge of the stripe B to the idle shuttle in the box, it being assumed that the shuttle S carries white thread and at this instant is the working shuttle. The mechanism provided by this invention severs such threads as those shown at w and b, Fig. 6, from the selvage edge of the fabric.

Referring more particularly to Figs. 1 to 4 inclusive, it will be seen that the mechanism shown comprises a guide 2 which engages the selvage edge of the web W in the region between the fell of the goods and the sand roll of the loom. This guide is U-shaped in cross section with the legs of the U lying, respectively, above and below the web of cloth, as best shown in Fig. 2. The guide is mounted rigidly on a bracket 3 which is secured adjustably on a horizontal rod 4, and this rod is arranged to have a limited axial sliding movement in the main frame 5 of the mechanism, this frame being bolted to the breast beam 6, Fig. 1, or to any other convenient support on the loom. A light coiled spring 7, encircling the rod 4, acts through the bracket 3 to hold the guide 2 yieldingly against the selvage edge of the web W.

It will be observed that the web W travels from the neighborhood of the lay 8, Fig. 1, toward the breast beam 6. As the web enters the guide 2, the selvage edge passes very close to the path of operation of a knife or cutter 10 which cooperates with the guide to sever any threads extending from the selvage. The cutter comprises a blade rigidly secured by a screw 12, Fig. 4, on an actuator arm 13. The actuator is secured fast to the rod 4 which serves as a pivot for the actuator. As the blade swings up and down it rubs against the side of the guide 2 and sweeps across a notch 14, Figs. 3 and 4, at the forward part of the guide, the lower wall of this notch forming, in effect, a stationary shearing blade to cooperate with the cutter blade 10 in severing the threads. A spring 19 acts through the rod 4 to hold the cutter against the guide 2. The actuator is arranged to be struck and operated by the lay 8, the lay imparting the cutting stroke.

to the cutter while a spring 15 moves the actuator back to position for its next actuation by the lay.

There is considerable tendency for the loose threads at the selvage to hug the selvage or to cling to the margin of the cloth, and in order to facilitate the severing of these threads from the goods, two mechanisms preferably are provided to operate successively on the marginal portion of the cloth to carry such threads outwardly away from the selvage and into position to be severed. One of these mechanisms comprises a roll 16, Fig. 1, having a series of spiral grooves on its peripheral surface which press the web of cloth against a depression 17 in the frame piece 18, and at the same time draw outwardly any loops or threads extending from the selvage edge of the cloth. In order to rotate the roll 16 it is secured on the end of a burr or temple roll 20 of the porcupine type, the barbs of this roll projecting into the cloth and being rotated by it as the web of cloth moves toward the cloth beam. Both the rolls 16 and 20 are mounted on a stationary shaft 21 supported by a bracket 22 that is adjustably secured to the frame 5 so that the pressure of the burr 20 on the cloth may be adjusted. The other mechanism for drawing the threads away from the selvage comprises fingers 25 and 26 arranged to engage, respectively, with the upper and lower surfaces of the web of cloth and operative to bear on the cloth at opposed points. The upper finger 25 is pivoted at 27, Fig. 2, to a part of the lower finger 26 and a spring 28, Fig. 2, coiled around the pivot stud 27, tends to hold the upper finger in contact with the lower finger. The latter finger is mounted on an arm 30, Fig. 2, which is adjustably secured by a screw 31 to a lever 32. This lever has a flattened central portion which is pivoted in the slot of a forked stud 33 having a pivot shank 34, Figs. 3 and 4, which is supported in a downwardly extending arm 35 of the bracket 3. A bail shaped end 36 is formed on the lever 32 and is located in a socket provided in the actuator 13.

It will be evident from an inspection of Figs. 2 and 4 that when the actuator 13 is moved backwardly, this movement will be transmitted through the lever 32 and arm 30 to the finger 26, and will result in moving both fingers transversely across the margin of the cloth while they still continue to grip the cloth due to the action of the spring 28. The inner corners on these fingers will act during this movement to catch any loop of thread attached to the portion of the selvage across which they move, and pull such a loop outwardly, as indicated in Fig. 7, into position to be severed by the cutter 10. It will be noted that the

path of movement of the lower finger is so related to the position of the guide 2 that the cloth is held firmly in contact with the finger during the movement of the finger, and that the upper finger is constantly pressed against the cloth by the spring 28, the two fingers engaging the cloth at opposed points. As the actuator 13 is returned by the spring 15, the connections above described will move the fingers 25 and 26 inwardly again across the selvage of the cloth in readiness for their next outward movement which will be produced by the motion of the lay.

When a shuttle has been in operation and is moved into an idle position in the box, and another shuttle carrying a filling of a different color is brought into operation, a filling thread will be left extending from the selvage edge of the web of cloth to the idle shuttle. This is illustrated in Fig. 1 in which the shuttle 37 is in an idle position in the box 38, and the thread *t* runs from the selvage of the web *W* to the shuttle 37. In the particular instance shown the shuttle 37 has been out of operation for a considerable length of time and during its period of idleness the web *W* has advanced far enough to carry thread *t* almost to the cutter 10. It is essential that when this thread has been severed it be gripped at some point so that when the shuttle 37 is again brought into operation it will lay a thread across the shed. It will be obvious that if the thread *t* were not so gripped the end of the thread would go through the shed with the shuttle. For this purpose upper and lower rolls 40 and 41, respectively, Figs. 4 and 5, are arranged at the forward end of the mechanism, that is, the end toward the lay, so that they can grip such a thread. These rolls are mounted in a temple frame 42 which is slidably connected with the main frame 5 of the trimming mechanism by two screws 43-43 that project downwardly through slots formed in the forward part of the frame 5. The temple frame, in addition to being guided on these screws, is also guided by two horizontal rods, one of which is shown at 44 in Figs. 3 and 4. Springs 45, encircling these rods, press the temple frame outwardly away from the trimmer frame and toward the lay. A temple roll 46 is mounted in the frame 42 and is rotated by the takeup movement of the cloth, and the thread gripping roll 40, above mentioned, rotates with the temple roll 46, both of these rolls being mounted on a shaft 47. The lower thread gripping roll 41 is rotated by its contact with the upper roll 40, the roll 41 being loosely mounted on a shaft 49. This shaft is supported in a slide 50 which is mounted in a short vertical slot formed in the frame 42, and a spring 51 acts through the slide 50 to press the roll 41 upwardly against the roll 40. The end of the roll 41

preferably is bevelled and grooved to bear against the bevelled surface 48 of the temple roll 46, these two bevelled surfaces cooperating to facilitate the movement of a loop 5 or thread outwardly away from the selvage of the cloth between the rolls 40 and 41.

After a change in shuttles has been made, the thread running from the selvage to the idle shuttle is carried backwardly into the 10 grip of the rolls 40 and 41, and they continue to hold the thread until the shuttle is again brought into operation. In the meantime the end of the thread attached to the selvage may have been severed by the cutter 15 10. In Fig. 1 the thread t' is shown still gripped by the rolls 40 and 41 after the shuttle to which it runs has been shot through the shed. This view assumes that a change in shuttles has just been made, but 20 for clearness the shuttle just put out of action and its thread are not shown.

Since the shaft 21 on which the worm 16 and temple roll 20 are mounted is supported only at one end of the mechanism shown, a 25 spring 52, Figs. 1 and 4, is arranged to bear on the outer or unsupported end of this shaft. One end of this spring is secured under a screw 53 on the temple frame 42, while its other end bears on a screw 54 30 which is threaded into a small bracket through which the outer end of the shaft 21 projects. This spring assists in holding the rolls 16 and 20 downwardly in firm engagement with the web of cloth.

It will now be appreciated that this invention provides a selvage trimmer which, considering the nature of the work performed, is of relatively simple construction, is entirely automatic in its action, and can 40 be manufactured economically. Since the mechanism, when mounted in a loom, is operated entirely by the lay, it requires no independent driving mechanism. The fact that the cutter, selvage guide 2, and the fingers 24 and 25 are all mounted on a common support and move laterally in unison as the spring 7 operates to hold the guide 2 against the selvage edge of the cloth, is an important advantage in maintaining a 45 definite and desired relationship between these parts and the selvage of the goods, notwithstanding the peculiar movements imparted to the fabric by the beatup of the lay and the takeup motion of the cloth.

While we have herein shown and described the best embodiment of our invention that we have so far devised, it will be evident that the invention may be embodied in other forms without departing from the spirit 55 or scope thereof.

Having thus described our invention, what we desire to claim as new is:

1. A selvage trimmer comprising, in combination, cutting mechanism for severing 60 loose threads extending from the selvage

edge of the cloth, a guide for engaging the selvage edge of the cloth and relatively guiding said edge and said cutting mechanism, and means for yieldingly holding said guide against the selvage edge of the cloth, where- 70 by a definite relationship is maintained between said cutting mechanism and said selvage edge.

2. A selvage trimmer comprising, in combination, cutting mechanism for severing 75 loose threads extending from the selvage edge of the cloth, means for relatively guiding said selvage edge and said cutting mechanism to maintain a definite relationship between them notwithstanding variations in the position of said edge as it moves past said cutting mechanism, and rotary means for operating on the cloth immediately in front of said cutting mechanism to draw 80 said loose threads away from the selvage 85 edge of the cloth and into position to be severed by said mechanism.

3. A selvage trimmer comprising, in combination, a guide for engaging the selvage 90 edge of a travelling web of cloth, cutting mechanism for severing loose threads extending from said edge as the threads enter 95 said guide, and means for acting on said threads immediately in front of said guide and as they approach said guide to draw them away from the selvage into position to facilitate said severing operation.

4. A selvage trimmer comprising, in combination, a U-shaped guide for engaging the 100 selvage edge of a travelling web of cloth, a cutter cooperating with said guide to sever loose threads extending from said edge, and means for operating on said threads as they approach said guide to move them into position to facilitate said severing operation. 105

5. A selvage trimmer comprising, in combination, a guide having a slot therein to receive the selvage edge of a travelling web of cloth, a cutter cooperating with said guide to shear loose threads from said selvage, and means for drawing said loose threads away 110 from the selvage of the cloth as they approach said cutter to position them for severing by said cutter.

6. A selvage trimmer comprising, in combination, a guide for engaging the selvage 115 edge of a travelling web of cloth, a cutter for severing loose threads extending from said edge, said guide serving to determine the relationship between said edge and cutter, and a plurality of devices arranged to act on the margin of the cloth as it approaches said cutter to draw said loose threads away from the selvage and into position to facilitate said cutting operation. 120

7. A selvage trimmer comprising, in combination, a guide for engaging the selvage 130 edge of a travelling web of cloth, a cutter associated with said guide and operative to sever loose threads extending from said edge,

cooperating fingers arranged to extend across the margin of the cloth and operative to yieldingly engage the upper and lower faces of the cloth at opposed points as the cloth 5 travels toward said cutter, and means for moving said fingers outwardly across the selvage while they continue to grip the cloth.

8. A selvage trimmer comprising, in combination, a guide for engaging the selvage edge of a travelling web of cloth, a cutter associated with said guide and operative to sever loose threads extending from said edge, cooperating fingers arranged to extend 10 across the margin of the cloth and operative to yieldingly engage the upper and lower faces of the cloth at opposed points as the cloth travels toward said cutter, a common support for said guide, cutter, and fingers 15 mounted for movement transversely to the selvage of the fabric and in a plane approximately parallel to the cloth, and means for yieldingly acting through said support to hold said guide against the selvage edge of 20 the cloth.

9. In a loom, the combination of a guide for engaging the selvage edge of the web of cloth being woven, a cutter associated with said guide for severing loose threads extending 25 from said edge, cooperating fingers arranged to extend across said selvage edge and to engage, respectively, the upper and lower faces of the cloth at opposed points, yielding means acting through said fingers 30 to cause them to grip the cloth, an actuator for said cutter arranged to be operated by the lay, and connections between said actuator and said fingers for causing the operative movement of the actuator to move said 35 fingers outwardly across the selvage edge while they grip the cloth, whereby they are operative to draw outwardly loose threads extending from the selvage edge of the cloth.

10. A selvage trimmer comprising, in combination, cutting mechanism for severing loose threads extending from the selvage edge of a travelling web of cloth, and rotary and reciprocating devices arranged to act 40 on the margin of the cloth as it approaches said mechanism to position said threads for severing by said mechanism.

11. A selvage trimmer comprising, in combination, cutting mechanism for severing loose threads extending from the selvage 45 edge of a travelling web of cloth, reciprocating devices mounted immediately in front of said mechanism for acting on the marginal portion of the cloth as it approaches said mechanism to draw the loose threads 50 into position to be severed, and rotary means in front of said devices for acting in a similar manner on said threads.

12. A selvage trimmer comprising, in combination, a cutting mechanism for severing 55 loose threads extending from the selvage

edge of a travelling web of cloth, and rotary means in front of said mechanism and arranged to be operated by the movement of the cloth for moving said threads outwardly away from the selvage edge and into position to be severed by said cutting mechanism. 70

13. A selvage trimmer comprising, in combination, a cutting mechanism for severing loose threads extending from the selvage 75 edge of a travelling web of cloth, and a rotary device having spiral cloth engaging members arranged to operate on the margin of the cloth immediately in front of said cutting mechanism to move said threads into 80 position to be severed by said mechanism.

14. A selvage trimmer comprising, in combination, cutting mechanism for severing loose threads extending from the selvage 85 edge of a travelling web of cloth, a rotary device for engaging the margin of the cloth as it approaches said cutting mechanism to move said loose threads into position to be severed by said mechanism, and a temple roll driven by the cloth for rotating said 90 device.

15. In a box loom, the combination of cutting mechanism for severing loose threads extending from the selvage edge of the web of cloth being woven, mechanism for acting 95 on the marginal portion of the cloth as it approaches said cutting mechanism to draw said loose threads outwardly away from the selvage edge into position to be severed by said cutting mechanism, and rotary means in front of said mechanism for gripping a thread running from the selvage to an idle bobbin. 100

16. In a box loom, the combination of cutting mechanism for severing loose threads extending from the selvage edge of the web of cloth being woven, mechanism for acting on the marginal portion of the cloth as it approaches said cutting mechanism to draw said loose threads outwardly away from the 110 selvage edge into position to be severed by said cutting mechanism, rolls mounted in front of said devices for gripping a thread running from the selvage to an idle bobbin, and a temple roll driven by the cloth and arranged to drive said rolls. 115

17. A selvage trimmer comprising, in combination, cutting mechanism for severing loose threads extending from the selvage 120 edge of the cloth, and means for relatively guiding said selvage edge and said cutting mechanism to maintain a substantially constant relationship between them, both in the plane of the cloth and also at right angles to said plane, notwithstanding the tendency of said edge to vary in position as it moves past said cutting mechanism.

18. A selvage trimmer comprising, in combination, cutting mechanism for severing 130 loose threads extending from the selvage

edge of the cloth, means for relatively guiding said selvage edge and said cutting mechanism to maintain a substantially constant relationship between them, both laterally 5 and vertically with reference to the selvage edge, notwithstanding the tendency of said edge to vary in position as it moves past said cutting mechanism, and means immediately in front of said cutting mechanism 10 for drawing said loose threads away from the selvage edge and into position to be severed by said cutting mechanism.

19. A selvage trimmer comprising, in combination, cutting mechanism for severing 15 loose threads extending from the selvage edge of the cloth, and mechanism for rela-

tively guiding said selvage edge and said cutting mechanism both laterally and vertically of the cloth and including means for engaging said selvage edge and guiding said cutting mechanism in the plane of the cloth to maintain automatically a substantially constant lateral relationship between said edge and said cutting mechanism notwithstanding variations in the position of said edge as it moves past said cutting mechanism. 20 25

In testimony whereof we have signed our names to this specification.

EUGENE J. STANTON.
LOUIS G. ROBERTS.
